UNITED STATES PATENT OFFICE

RUFUS MELVIN OVERLANDER, JR., AND EVARTS WEBSTER OVERLANDER, OF
NEW YORK, N. Y.

DESK HOLDER FOR WATCH MOVEMENTS

Application filed May 10, 1928. Serial No. 276,655.

Many persons are the proud possessors of old fashioned key-wind watches, but because of the fact that such watches have, so to speak, "gone out of style" they are no longer 5 carried but are carefully laid away with the other family relics to be passed down to posterity as heirlooms, ad infinitum.

This invention has for an object to provide improved holding means whereby these now 10 unused watches may be transformed into ornamental desk clocks and thereby be caused to serve a useful purpose.

This invention contemplates providing an ornamental base, preferably in miniature 15 imitation of an old fashioned grandfather's clock, formed with a cavity to receive the watch movement and providing means cooperating with the base to hold the watch movements against both bodily and rotative 20 movements.

Another object of the invention is to provide a substantially dust-proof casing for the watch movement and so to construct the casing and the means for holding the watch 25 movement that access readily may be had to the movement for the purpose of winding, setting and adjustment.

Still another object of this invention is to provide a suitable support which will securely 30 hold the watch movement in a predetermined position and preclude any pressure on the movement which might interfere with the proper functioning thereof.

This invention also has for an object to 35 render available a novel holder for watches whereby a complete watch readily may be inserted therein and serves as a desk or similar clock.

Drawings depicting preferred forms of 40 the invention form a part of this disclosure and in said drawings:—

Figure 1 is a perspective view of a novel 45 holder for watch movements embodying the present invention. Fig. 2 is an enlarged view, partly in section, of the upper portion of Fig. 1 showing a watch movement held therein. Fig. 3 a rear view of the upper portion of Fig. 1 with the dust door shown only in dotted lines to expose to view the watch 50 movements therein. Fig. 4 is a side elevation

of a retaining collar, later to be described. Fig. 5 is a face view of a portion of the collar shown in Fig. 4. Fig. 6 is a face view of a spacer ring later to be referred to. Figs. 55 7 and 8 are side and face views respectively of a modified retaining collar. Fig. 9 is a vertical section through the upper portion of a modified holder, showing a complete watch held therein. Fig. 10 is a rear view of Fig. 9.

Referring more specifically to the drawings the invention is disclosed as comprising a body member 1 preferably, but not necessarily, in the form of a miniature grandfather's clock. Adjacent its upper end the body member is formed with a cylindrical bore or cavity 2 adapted to receive a conventional watch movement M. At the face of the member the bore is of reduced diameter as shown at 3 in Fig. 2, thereby providing 60 a shoulder 4 against which seats a suitable crystal 5. Intermediate the crystal 5 and the watch movement M there is a split metallic ring 6. This ring is adapted to expand into engagement with the walls of the bore 2 and 65 performs the dual function, first of retaining the crystal 5 in contact with the shoulder 4 and second of serving as a spacer member between the crystal and the dial D of the watch movement, thereby to prevent the 70 hands of the watch from contacting with the crystal, inasmuch as the dial D bears against the ring 6 the watch movement is positively 75 held against movement outward. To hold the movement against inward movement a retainer 7, preferably in the form of a collar, is 80 fitted into the bore 2 and has one edge thereof in engagement with the rear of the watch movement. The collar 7 may be held in the bore 2 by any suitable means, such for example, as by the screws 8 threaded into the 85 body member 1.

An important feature of this invention resides in the point of engagement between the collar and the movement. As is well understood watch movements include arms, designated generally as x, having relatively thick foot portions adapted to be secured to the bearing plates by screws as 9 (Fig. 3) and relatively thin overhanging unsupported 90 95 100

ends which provide bearings for the various pintles. The collar 7 is so constructed and arranged that it engages the arms α only adjacent their foot portions and outwardly of their fastening screws. This precludes exerting any pressure on the unsupported overhanging portion of the arms which otherwise might deflect the arms, and the bearings carried thereby, and interfere with the proper operation of the watch movement.

To exclude dust and moisture from the watch movement a swinging door 10 is pivoted at 11 to the back of the body member and is adapted completely and tightly to close the rear end of the bore 2. The crystal 5 securely closes the forward end. The door 10 may, however, readily be swung to the position illustrated in dotted lines in Fig. 3 to permit the user to apply a suitable key to the square shaft 12 for winding or to the square shaft 13 for setting.

To maintain the watch movement in a predetermined position and to prevent it from rotating in the bore 2, when subjected to the strain of winding, the collar 7 is provided with a suitable anchor 14 adapted to fit between and engage two of the arms α . In certain types of watch movements the pintles are journaled in a solid plate instead of in the arms α as shown in Fig. 3. When such movements are to be held the collar 7 may be provided with an anchor pin 15 as shown in Figs. 7 and 8, and this pin may be inserted in one of the screw holes normally used to receive the screws which hold the watch movement in its case.

Figs. 9 and 10 show a modified holder adapted to receive a complete watch case W with the movement therein. In this form, in addition to the bore 2 the body member 1 is formed with a cavity 16 adapted to receive the stem S and ring of a watch. The bore 2 and cavity 16 are connected together by means of a restricted slot 17 adapted to receive the neck of the watch stem. The walls 18 of the slot 17 serve as abutments for the stem and thereby preclude rotation of the watch in the bore 2. The watch may be in retained predetermined position with its crystal c in the reduced bore 3 by means of a block 19 fitted within the bore 2 behind the watch and held therein by frictional engagement with the walls of said bore.

This modified holder enables the owner of a watch to obtain double use therefrom. For example, a business man may, upon reaching his office in the morning, remove his watch from his pocket and place it in one of these novel holders, whereupon his watch serves throughout the day as a novel and ornamental desk clock. Before departing for home in the afternoon, he may readily remove his watch from the holder, replace it in his pocket none the worse for its double use.

From the foregoing it will be perceived

that we have provided an improved holding means for watch movements which is capable of transforming unused and discarded watches into useful and ornamental desk clocks. Also that the modified construction above described enables a watch owner to obtain double duty from his watch, to wit:—first as a pocket watch and second as a desk clock.

Having thus described our invention, what we claim and desire to secure by Letters Patent is:—

A device of the character described combining a body member provided with a cylindrical bore; a crystal fitted within said body member adjacent one end of said bore; a watch movement arranged within said bore behind said crystal, said watch movement including a plurality of pindle-supporting arms held in place by retaining screws passed through their outer ends; a retaining collar secured within said bore behind said watch movement and affording means to prevent displacement of said watch movement, said collar being so constructed and arranged as to engage said arms only outwardly of their retaining screws.

In witness whereof, we have hereunto subscribed our names.

RUFUS MELVIN OVERLANDER, Jr.
EVARTS WEBSTER OVERLANDER.
